UNITED STATES PATENT OFFICE

149,504

DESIGN FOR A PERFUME CONTAINER OR THE LIKE

Abraham Levy, New York, N. Y., assignor to Parfum L'Orle, Inc., New York, N. Y., a corporation of New York

Application May 15, 1946, Serial No. 129,723

Term of patent 7 years

(Cl. D58—8)

To all whom it may concern:

Be it known that I, Abraham Levy, a citizen of the United States, and a resident of the city, county, and State of New York, with a post office address at 6 East 39th Street, in the Borough of Manhattan, city and State of New York, have invented a new, original, and ornamental Design for Perfume Container or the like, of which the following is a specification, reference being had to the accompanying drawing, forming part hereof, in which:

Fig. 1 is a front elevational view of a perfume container or the like, embodying my new design.

Fig. 2 is a rear view of the same.

Fig. 3 is a plan view of the same.

I claim:

The ornamental design for a perfume container or the like, as shown.

ABRAHAM LEVY.
